UNITED STATES PATENT OFFICE.

AARON P. STORRS, OF OWEGO, NEW YORK, ASSIGNOR TO STORRS MICA COMPANY, OF OWEGO, NEW YORK, A CORPORATION OF NEW YORK.

MICA CHIMNEY.

1,000,047.

Specification of Letters Patent. Patented Aug. 8, 1911.

Application filed March 12, 1909. Serial No. 482,905.

To all whom it may concern:

Be it known that I, AARON P. STORRS, a citizen of the United States, residing at Owego, Tioga county, State of New York, 5 have invented a new and useful Mica Chimney, of which the following is a specification.

The object I have in view is the production of cheap, simple and durable means for 10 attaching the burner cap to the chimney. These and further objects will appear from the following specification and accompanying drawings, considered together or separately.

15 In the drawings: Figure 1 is an elevation of one form of mica chimney embodying my invention; Fig. 2 is a bottom view thereof; Fig. 3 is a perspective view of the lower band or strip, before it is curved and before 20 it is attached to the mica. Fig. 4 is a section on the line 4—4 of Fig. 3. Fig. 5 is a section on the line 5—5 of Fig. 2. Fig. 6 is a section on the line 6—6 of Fig. 2. Fig. 7 is a side view of a lower band, slightly 25 modified from that shown in the preceding views. Fig. 8 is a sectional view of a structure made with the band shown in Fig. 7, such view being similar to Figs. 5 and 6.

30 In all of the views like parts are designated by the same reference characters.

In carrying out my invention, I provide a chimney formed of one or more mica sheets 1 with an upper band 2 and lower band 3. The edges of the sheets overlap 35 and are secured together by eyelets 4, as shown.

5 are the usual ventilating openings and 6 is the burner cap.

The size of the chimney, the ventilating 40 openings, burner cap and the details of the parts will be modified in accordance with the use to which the chimney is put.

The chimney illustrated in Figs. 1 and 2 is of a type employing an incandescent mantle. The upper band 2, as shown, is made 45 of sheet metal, doubled over the edge of the mica and holding the latter in proper shape and protecting the upper edge. The lower band 3 is made as shown in Fig. 3 or 7.

50 Referring to Figs. 3 and 4, it will be seen that the band 3 is folded at 7, and doubled back upon itself at 8. The band is again folded at 10 and again doubled back at 11, leaving an opening 12 between the parts 8 55 and 11. The doubled back portion 8 is now

of less depth than the straight portion 9. The portion 13 of the straight portion 9 extends below the fold 10. The mica sheet or sheets is inserted in the opening 12, and is secured therein by pinching the parts 8 60 and 11 together. Preferably, the mica sheet is inserted in the band while the latter is straight (as shown in Fig. 3). Afterward, the band is bent to circular form and the two ends are secured together by an eyelet or rivet passing through the openings 14—14 in the ends of the band. This eyelet also passes through the overlapping sheets of mica. When the band is bent to circular form, the fold 10 and doubled back 70 portions 8 and 11 must be arranged to be on the inside. The fold 10 will produce an annular ledge and the portion 13 will produce an annular rim or flange extending below such ledge. 75

The burner cap 6 may be provided with a circular plate or disk 15. The disk or plate 15 of the burner cap is designed to fit as snugly as possible within the portion 13 and abut upon the fold 10. When in this position the portion 13 is rolled over inward or otherwise folded in at 13^a (see Figs. 5, 6 and 8), thus constituting a fastening for the burner cap. The fold 10 forming a ledge, acts as a stop and serves to prevent the 85 burner cap entering the chimney any farther. The portion 13, being folded over, acts as a fastening means to hold said burner cap in engagement with the ledge.

For the purpose of supporting the burner 90 cap, should the bottom of the chimney be accidentally formed of too great a diameter, so that the burner cap would not engage with the fold 10—I may provide the portion 13 with cut away portions forming tongues 95 16 (as shown in Fig. 3). These tongues are bent inward at 16^a (see Fig. 5) and extend inward a greater distance than the width of the fold 10. The plate 15 of the burner cap will be embraced, therefore, between the 100 tongues 16^a and the turned in portions 13^a. For the purpose of adding to the strength of the plate 15, the same may be dished at 17, although this is not essential,—a flat plate being illustrated in Fig. 8. According to 105 my invention, therefore, the plate 15 may be clamped between the fold 10 and the turned in portion 13^a (as shown in Fig. 8) or between the tongues 16^a and the turned in portion 13^a, as shown in Figs. 5 and 6, if such 110

tongues be employed. Where the tongues 16^a are employed they abut against the ledge 10, which thereby serves as a backing to prevent the plate being forced inward. It is therefore plain, that whether the tongues be used or not, the burner cap is clamped between the ledge and the flange 13^a. This results in a strong and rigid structure, and permits the employment of thin and flexible 10 metal bands.

In accordance with the provisions of the patent statutes, I have described the principle of my invention, together with the apparatus which I now consider to represent 15 the best embodiment thereof; but I desire to have it understood that the apparatus shown is merely illustrative and that the invention can be carried out in other ways.

Having now described my invention, what 20 I claim as new and desire to secure by Letters Patent, is:—

1. A mica chimney and a burner cap, said chimney having a ledge and a flange, between which the cap is clamped.

2. In combination with a mica chimney 25 having a lower band with a ledge, of a burner cap and means on the band for clamping the cap against the ledge.

3. A mica chimney with a folded lower band, forming a ledge and a flange, in combination with a burner cap lying within the band, the flange being turned inward to hold the cap in place.

4. A mica chimney having a lower band, 35 said band being folded over the lower edge of the mica and forming a ledge, and a depending portion, split to form fingers and flanges in combination with a burner cap, said cap resting against the fingers and the flanges being turned over upon the cap and 40 retaining it in place.

This specification signed and witnessed
March 6th, 1909.
